CLAIM

The ornamental design for a chin spoiler, as shown and described.

DESCRIPTION

FIG. 1 is a perspective top view of the chin spoiler of the present invention;

FIG. 2 is a front elevation side view thereof;

FIG. 3 is a rear elevation view thereof;

FIG. 4 is a left perspective side view thereof;

FIG. 5 is a right perspective side view thereof;

FIG. 6 is a top view thereof; and,

FIG. 7 is a bottom view thereof.

The broken lines depict portions of the chin spoiler that form no part of the claimed design.
